WILLIAM PARKIN, OF TAUNTON, MASSACHUSETTS, ASSIGNOR TO
REED AND BARTON, OF SAME PLACE.

Design No. 3,422, dated March 23, 1869.

DESIGN FOR A BOTTLE-STAND, OR CASTER

The Schedule referred to in these Letters Patent and making part of the same.

To all persons to whom these presents may come:

Be it known that I, WILLIAM PARKIN, of Taunton, in the county of Bristol, and State of Massachusetts, have invented a new and ornamental Design for a Bottle-Stand, or Caster; and I do hereby declare the same to be fully described in the following specification, and represented in the accompanying drawing, which is a perspective elevation of it.

In such drawing—

The base, A, of the caster, is exhibited as a short, hollow, cylindrical dish, provided with a series of projections, or brackets, *a a a*, and with a series of mailed figures, or warriors, *b b b*, supported thereon.

The base has, projecting from its lower edge, a series

of feet, D, each of which has, on its external surface, an Egyptian head, *c*, in *alto-relievo*.

There are also four balls, *d*, on the upper edge of the base.

The rotary bottle-stand, B, and the handle, C, make no part of my present design, which has reference entirely to the base-part, A.

I claim the ornamental design of the said base-part, the same being as represented, and as above explained.

WILLIAM PARKIN.
